CURRENT SOURCES

Application filed November 14, 1929, Serial No. 407,097, and in Germany November 8, 1928.

This invention relates to means for supplying direct current free from alternating current components to the filaments of thermionic tubes, and in particular to apparatus of the above nature in which the various elements are arranged in a novel manner such that highly improved results may be obtained with apparatus of reduced size.

The invention has been illustrated in the attached drawing in which,

Figure 1 shows a filter circuit interposed between a source of current and a load;

Figure 2 shows a filter circuit arranged in accordance with applicant's novel invention; while,

Figure 3 shows a modification of the arrangement of Figure 1.

When supplying the filament current for thermionic tubes from a rectified alternating current source or a pulsating direct current source (rectifier, direct current network) it is necessary to free the direct current from alternating current components. With this end in view mostly one or more filter chains are employed, for instance, in a circuit arrangement of the kind shown in Figure 1, where E and e the direct current and the alternating current components of the supply or feed potential, L a choke-coil, C a shunt or parallel condenser, R a series resistance, and W the load resistance, i. e., the resulting filament resistance of all of the tubes.

A simple calculation shows that the relation M between the alternating current component e_w across the terminals of load W and the alternating current component e of the source, when

$$\frac{1}{\omega C}$$

is considerably lower than $(R+W)$, is expressible by the equation

$$M = \frac{W}{e} = \frac{W}{R(1 - \omega^2)LC} \quad (1).$$

Now, this scheme involves the disadvantage that the inductance of choke-coil L owing to the biasing magnetization due to the relatively high direct current component is very considerably diminished so that it must

be made of relatively large dimensions. Furthermore, C must become very high whenever $R+W$ becomes small, i. e., when relatively large filament currents have to be supplied.

Since, for instance, in receivers the tubes take dissimilar filament currents, with the largest current being required by the last tube or the power stage (which furthermore, because of low amplification is comparatively insensitive to the alternating current component of the filament current), recourse is had to the scheme shown in Fig. 2 with the end in view of diminishing the biasing magnetization of the choke-coil L by the direct current. Referring to Fig. 2, w and u denote, respectively, the filament resistance of the input tubes and the power tubes, and r_w and r_u the corresponding series resistances. What flows here exclusively through the choke-coil L is the filament current of the input tubes which is considerably lower than that of the end or power stage.

However, this circuit arrangement involves the drawback that here two series resistances are required, and that the energy dissipated therein is comparatively large.

Now, according to the invention arrangements are so chosen that the total filament current is made to flow through a joint series resistance and that the choke-coil is included only in the lead of the filament circuit of all or part of the input tubes, in a way as shown in Fig. 3.

This arrangement not only allows of combining the advantage residing in a reduction of the biasing magnetizing current of the choke-coil L with the advantage of saving or dispensing with a distinct series resistance r_u as in Fig. 2, but it is also feasible to dispense with the parallel condenser C or to reduce the size of the same considerably inasmuch as the potential distribution as regards the input tubes is fundamentally different. In practice the reduction ratio

$$m = \frac{e_w}{e}$$

of the alternating current components of the

potential is far more favorable than in the circuit schemes hereinbefore indicated.

There is in this case:

$$5 \quad e_u = e \cdot \frac{u}{r+u} \sim e \frac{u}{r} \quad (2)$$

presupposing that $\omega L > u$.

Furthermore

$$10 \quad e_w = e_u \cdot \frac{w}{w + e \omega L} \quad (3)$$

From (2) and (3) there follows this reduction ratio:

$$15 \quad m = \frac{e_w}{e} \sim \frac{u}{r \left(1 + j \frac{\omega L}{w} \right)} \quad (4)$$

Comparing Equations (1) and (4) for the reduction ratio M and m , respectively, the superiority of the circuit scheme here disclosed follows from the relation

$$25 \quad x = \frac{M}{m} : \\ x \sim \frac{W r}{u R} \cdot \frac{1 + j \frac{\omega L}{w}}{1 - \omega^2 L C} \quad (5)$$

30 In practice there is $u < w$ and $u = W$, furthermore $r = R$, whence

$$35 \quad x \sim \frac{1 + j \frac{\omega L}{w}}{1 - \omega^2 L C} \quad (6a)$$

In practice it is possible to put with sufficient approximation:

$$40 \quad x = \frac{1}{w \omega C} \quad (6b)$$

Hence, the circuit schemes here compared result in similar reduction ratios when

$$45 \quad w = \frac{1}{\omega L}$$

For instance, if w amounts to around 100 ohm—and this is frequently the case—then 50 the circuit scheme shown in Fig. 1, in order to be equivalent as regards reduction ratio, would have to contain a condenser C of 30 mfd., at 50 cycles, and of 3 mfd. at 500 cycles. Hence, in the circuit arrangement of this invention there is saved a condenser of 30 and 55 3 mfd., respectively, under conditions as cited in the above numerical example.

I claim:

1. In apparatus for supplying the filaments 60 of thermionic tubes having different amplification factors, a source of pulsating direct current, means for connecting the filaments of the high amplification tubes in series through an inductance and resistance with 65 said source, and means for connecting the re-

maining tube filaments through said resistance in series with said source.

2. Means for supplying heating currents to the emission elements of a plurality of thermionic repeaters of signaling apparatus, from a source on which alternating current components are superposed and for preventing said components from modulating the repeated signals, including a source of current having alternating current, components superposed thereon, a filter inductance, means for connecting the emission elements of the tubes in the first of said repeaters in series with said source and said filter inductance, a resistance, and means for connecting the emission elements of the tubes in the last of said repeaters in series with said resistance, said filter inductance and with said source. 70 75 80

3. Means for supplying heating current to the emission elements of a plurality of repeater stages, each stage comprising at least one thermionic tube, the tubes of the initial stages having greater amplification factors than the tubes of the remaining stages, from a source of energy including alternating current components and for preventing said components from modulating the repeated signals comprising a resistance, a filter inductance, means for connecting the emission elements of the tubes having high amplification factors in 85 90 95 series with said inductance said resistance and said source, and means for connecting the emission elements of the other tubes in series with said resistance and said source.

4. In signalling apparatus comprising a plurality of space discharge devices some of which are utilized for high amplification purposes while others are utilized for low amplification purposes, means for energizing the cathodes of all of the space discharge devices comprising a source of fluctuating direct current, a resistance element, filtering means, means for forming a series circuit comprising the cathodes of the high amplification devices, the filtering means, the resistance and said source, and means for shunting the cathodes of the low amplification devices across the portion of the series circuit including the filtering means and the cathodes of the high 100 105 110 115 120 125 130 135 140 145 150 amplification devices.

RUDOLF RECHNITZER.
